UNITED STATES PATENT OFFICE.

GRACE H. SIMONSON, OF PELHAM HEIGHTS, NEW YORK, ASSIGNOR TO CHENEY BROTHERS, OF SOUTH MANCHESTER, CONNECTICUT, A CORPORATION OF CONNECTICUT.

DESIGN FOR A TEXTILE FABRIC.

49,713.

Specification for Design.

Patented Sept. 26, 1916.

Application filed June 16, 1916. Serial No. 104,132. Term of patent 3½ years.

To all whom it may concern:

Be it known that I, GRACE H. SIMONSON, a citizen of the United States, residing at Pelham Heights, Westchester county, New York State, have invented a new, original, and ornamental Design for Textile Fabrics, of which the following is a specification, reference being had to the accompanying drawing, forming a part thereof, wherein the

single figure is a plan view of a portion of a textile fabric illustrating my new design.

I claim—

The ornamental design for a textile fabric, as shown.

GRACE H. SIMONSON.
